UNITED STATES PATENT OFFICE.

FRANK E. MUELLER, OF CHICAGO, ILLINOIS, ASSIGNOR TO ROBERTS AND SCHAEFER COMPANY, OF CHICAGO, ILLINOIS, A CORPORATION OF ILLINOIS.

APPARATUS FOR LOADING COAL.

Application filed August 7, 1922. Serial No. 580,051.

To all whom it may concern:

Be it known that I, FRANK E. MUELLER, a citizen of the United States, residing at Chicago, in the county of Cook and State of Illinois, have invented a certain new and useful Improvement in Apparatus for Loading Coal, of which the following is a specification.

My invention relates to a process and apparatus for screening and delivering coal, and particularly to a process for screening, grading and delivering coal direct to the railroad car without dropping the coal and submitting it to the inevitable breakage caused by the usual drop from the graded coal bin to the car.

One object of my invention is to provide a means and process for separating coal into a number of grades and for feeding such grades selectively to a car on a track adjacent or beneath the bins. Another object is to provide means for carrying out the process above outlined at a maximum speed and with a minimum number of bins. An other object is to provide a means and process for conveying the coal from the bin gate and downwardly to the car rapidly but without breakage. Other objects will appear from time to time in the course of the specification.

I illustrate my invention more or less diagrammatically in the accompanying drawings, wherein—

Fig. 1 is a vertical section through a coal screening, storage and delivery installation;

Fig. 2 is a section on the line 2—2 of Fig. 1;

Figs. 3 and 4 are diagrammatic sections through coal spouts or chutes illustrated in Fig. 1;

Fig. 5 is a section through the lower portion of a variant form of plant;

Fig. 6 is a section on the line 6—6 of Fig. 5;

Fig. 7 is a section through the lower portion of another type of plant;

Fig. 8 is a section on the line 8—8 of Fig. 7;

Fig. 9 is a vertical section through the lower portion of another type of plant; and

Fig. 10 is a section on the line 10—10 of Fig. 9.

Like parts are illustrated by like characters throughout the drawings.

A is any suitable form of conveyor or elevator for conveying coal from the tipple or coal source to the screens through the opening A¹ in the house A².

B are bin walls supported by the vertical frame elements B¹. B² are the bin bottoms having inclined sides as at B³ leading to gates B⁴ with suitable opening and closing elements not shown in detail and adapted to be controlled by the chains B⁵ or otherwise. B⁶ is any suitable trimmers' walk.

C C¹ are shaker screens mounted on the oscillating elements C², the lower ends of which are affixed to the frame or support C³. The shaker screens are reciprocated in any suitable manner, for example by the links C⁴ C⁴ pivoted adjacent the end of each boom and oscillated by the eccentrics C⁵ or any other suitable mechanism actuated from a power source not herein shown.

Beneath the shaker screen C is the delivery hopper D, adapted to deliver screenings to the spouts D¹ D² shown in diagrammatic detail in Fig. 3, and provided with a selective gate D³ hinged as at D⁴. Beneath the upper portion of the screen C¹ is the feed hopper D⁵, which feeds to a pair of spouts D⁶ D⁷, similar to D¹ D² and, like D¹ D², adapted to deliver coal selectively to neighboring bins. Beneath the lower portion of the screen C¹ is another delivery spout D⁸, shown as delivering coal to a spiral chute D⁹ in the central bin of the five illustrated in Fig. 1.

Mounted beneath the lower end of the shaker screen C¹ is a picking table E, which is illustrated in Fig. 1 as an endless carrying belt. The material delivered from the outer end of the picking table passes down the chute E¹ and may be selectively delivered down the spouts E² E³ to the spiral chutes E⁴ E⁵, delivering to the two bins shown at the left of Fig. 1.

It will be understood that the various bins overlie the railroad track G, as shown, for example, in Fig. 2, the gates B⁴ lying substantially along the central axis of the track. Beneath the gates, and spaced above the track a sufficient distance to permit the passage of cars, is the conveyor G¹, illustrated in Fig. 1 as an endless belt, the details of which form no part of the present invention. This conveyor delivers coal to a reciprocating screen G², which is oscillated by

the link G^3 through any practical eccentric drive mechanism G^4 . Adjacent the screen G^2 is the reciprocating loading boom G^5 , adapted to be reciprocated by the link G^6 driven by the eccentric G^7 . The loading boom is pivoted, and any satisfactory means, not herein shown, are used for supporting, raising and lowering at will the outer end of the boom, without breaking the loading contact with the screen G^2 .

The fines which pass through the screen G^2 drop into the hopper H , and are gathered and carried by a spiral conveyor H^1 , which delivers to the screenings elevator H^2 , which in turn discharges them through the spout H^3 into the slack bin shown at the right hand of Fig. 1. The slack bin may be provided with a slack gate, and a chute H^4 direct to the underlying car, and of course positioned slightly to one side of the conveyor G^1 .

In the variant form shown in Figs. 5 and 6, K is an inclined lip or other form of screen which receives material from the conveyor G^1 and feeds to the apron loading boom K^1 , the details of which do not form part of the present invention. Otherwise the installation is identical with that shown in Fig. 1.

In the form shown in Figs. 7 and 8, the endless conveyor G^1 is replaced by a plurality of superposed conveyors L L^1 , adapted to be reciprocated in opposition by any suitable reciprocating means diagrammatically illustrated as at L^7 . L is the loading conveyor which receives material discharged from any of the storage bins and delivers it to the loading boom L^2 , hinged at the outer or left-hand end of L , as shown in Fig. 7. Any suitable means may be used for raising, lowering and supporting the outer end of the hinged boom. The loading conveyor is provided at any suitable point, as, for example, at L^8 in Fig. 8, with a re-screen, which deposits the fines or degradation on the lower conveyor L^1 , which in turn conveys it from left to right, as shown in Fig. 7, depositing it finally in the hopper L^4 , whence it is carried by the spiral screenings conveyors L^5 L^6 to the screenings elevator H^2 for delivery to the slack bin.

In the variant form shown in Figs. 9 and 10, the chutes M , M^1 , M^2 , M^3 and M^4 deliver coal to the upper loading boom N , down which it passes to the lower loading boom N^1 , the two loading booms being reciprocated by the links N^2 N^3 actuated by the eccentric or other suitable apparatus N^4 . The lower boom N^1 is pivoted and suitable means, of course, are provided for controlling its outer end. At N^6 in the upper boom a rescreen is provided, which delivers fines or degradation to the hopper N^8 , from which they are carried by the spiral conveyors N^7 N^8 to the screenings elevator H^2 .

It will be understood that while I have illustrated several practical applications of my invention many changes might be made in the number, size, shape and disposition of parts, and many combinations and changes in order of the steps of my process might be made, without departing from the spirit of my invention.

The use and operation of my invention are as follows:

Coal is delivered by any satisfactory means from a tipple or other coal source to a shaker screen or a succession of shaker screens, by which the coal is graded and passes through the various meshes or finenesses of screen to a plurality of classified storage bins, of which five are illustrated in the drawings. The material which passes over the screens may, if desired, be picked and is subsequently passed forward over the picking table and into classified bins. I so arrange the receiving hoppers screens and the delivery chutes that any class of coal, or coal from any particular screen or section of screen, may be delivered at will to more than one classified storage bin. If necessary, telegraph or spiral chutes may be provided to deliver coal downward to the bottom of the bin, to avoid breakage. In the installation I illustrate, a number of bins are aligned along the railroad track upon which the coal car travels, and the outlet gates are aligned over any suitable conveyor, which may be an endless conveyor belt or chain, or which may be some form of oscillating or reciprocating conveyor, the point being that this conveyor receives the coal from any desired bin or gate and conveys it without shock or breakage. The conveyor in the form shown in Fig. 1 delivers the coal to the rescreen G^2 , where the degradation is removed and the coal in its final, cleaned condition is delivered down an oscillating or shaking loading boom which lowers the coal without breakage and feeds it directly to the car bottom. The fines may be disposed of in any suitable manner but are frequently returned to a screenings elevator, which eventually drops them back into the slack bin.

In the form shown in Figs. 5 and 6, for a shaker loading boom an apron loading boom is substituted and a highly inclined lip screen is shown, but the general operation, of course, is the same.

In the form of Figs. 7 and 8 I substitute for the endless conveyor a plurality of superposed shaker booms or conveyors which reciprocate in opposition, the upper conveyor having at one or more points a re-screen which delivers fines or degradation to the lower conveyor, the lower conveyor delivering them to a screen conveyor or elevator. A loading boom is hinged to the upper loading conveyor and, of course, serves to

deliver coal directly to the car, as above described.

In Figs. 8 and 9 a reciprocating upper loading boom receives coal from the desired bin or gate and feeds it over a rescreen portion and thence to a separate shaker loading boom, which in turn delivers direct to the car. In Figures 9 and 10 I illustrate a plurality of chutes delivering coal to an upper boom or reciprocating conveyor, down which it passes to a lower boom N^1 , the booms or conveyors being separately reciprocated by the links N^2 , N^3 . The separate or lower shaker boom N^1 delivers the material directly to the car.

I claim:

1. In a material handling installation adapted to be aligned along and above a railroad track, a plurality of storage bins longitudinally aligned above said track, material feeding means in the bottom of each of said bins, a substantially horizontal conveyor aligned beneath said bins and feeding means and adapted to receive material from all of them, a loading boom adjacent one end of said horizontal conveyor and adapted to receive material therefrom and means for raising and lowering said boom.

2. In a material handling installation adapted to be aligned along and above a railroad track, a plurality of storage bins longitudinally aligned above said track, material feeding means in the bottom of each of said bins, a substantially horizontal conveyor aligned beneath said bins and feeding means and adapted to receive material from all of them, a loading boom adjacent one end of said horizontal conveyor and adapted to receive material therefrom and means for raising and lowering said boom, and screening means intermediate said horizontal conveyor and said loading boom.

3. In a material handling installation, a plurality of longitudinally aligned storage bins, material feeding means in the bottom of each of said bins, a substantially horizontal conveyor aligned beneath said bins and feeding means and adapted to receive material from all of them, a rescreening element adjacent the end of said horizontal conveyor, a loading boom adjacent the same end of said horizontal conveyor and adapted to receive therefrom the material, and means for raising and lowering said boom.

4. In a material handling installation, a plurality of longitudinally aligned storage bins, material feeding means in the bottom of each of said bins, a substantially horizontal conveyor aligned beneath said bins and feeding means and adapted to receive material from all of them, a rescreening element adjacent one end of said horizontal conveyor and a loading boom adjacent said rescreening element, said rescreening element being adapted to receive material from

said horizontal conveyor and to deliver it to said loading boom.

5. In a material handling installation, a plurality of longitudinally aligned storage bins, material feeding means in the bottom of each of said bins, a substantially horizontal conveyor aligned beneath said bins, and feeding means and adapted to receive material from all of them, an oscillating rescreening element adjacent one end of said horizontal conveyor and an oscillating loading boom adjacent said rescreening element, said rescreening element being adapted to receive material from said horizontal conveyor and to deliver it to said loading boom.

6. In a material handling installation, a plurality of longitudinally aligned storage bins, material feeding means in the bottom of each of said bins, a substantially horizontal conveyor aligned beneath said bins and feeding means and adapted to receive material from all of them, an oscillating rescreening element adjacent one end of said horizontal conveyor and an oscillating loading boom adjacent said rescreening element, said rescreening element being adapted to receive material from said horizontal conveyor and to deliver it to said loading boom, and separate means for oscillating said rescreening element and said loading boom.

7. In a material handling installation, a plurality of longitudinally aligned storage bins, material feeding means in the bottom of each of said bins, a substantially horizontal endless conveyor aligned beneath said bins and feeding means and adapted to receive material from all of them, an oscillating loading boom adjacent the end of said conveyor and adapted to receive material therefrom, and a rescreening element adjacent the point of delivery of the conveyor to the loading boom.

8. In a material handling installation, a plurality of longitudinally aligned storage bins, material feeding means in the bottom of each of said bins, a substantially horizontal endless conveyor aligned beneath said bins and feeding means and adapted to receive material from all of them, an oscillating loading boom adjacent the end of said conveyor and adapted to receive material therefrom, and a rescreening element adjacent the point of delivery of the conveyor to the loading boom, and separate means for oscillating said boom and conveyor.

9. In a material handling installation, a storage receptacle, means for feeding material from the bottom of said receptacle, a substantially horizontal conveyor beneath said receptacle and adapted to receive the material delivered therefrom, means for actuating said conveyor, a loading boom adjacent one end of said conveyor and axially aligned with it, and adapted to receive material therefrom, and a screening element ad-

adjacent the point of delivery of said conveyor to said loading boom.

10. In a material handling installation, a storage receptacle, means for feeding material from the bottom of said receptacle, a substantially horizontal endless conveyor aligned beneath said receptacle and adapted to receive material therefrom, an oscillating loading boom adjacent the end of said conveyor and adapted to receive material therefrom and a rescreening element adjacent the point of delivery of the conveyor to the boom.

11. In a material handling installation, a storage receptacle and means for feeding material from the bottom thereof, a substantially horizontal conveyor therebeneath and adapted to receive material therefrom, a screening element adjacent the delivery end of said conveyor and adapted to receive material therefrom, and a loading boom adjacent said screening element and adapted to receive material therefrom.

12. In a material delivery installation, a storage bin, material delivering means in the bottom thereof, a lateral conveyor adapted to receive material directly therefrom, an oscillating loading boom mounted adjacent the delivery end thereof and a rescreening element mounted intermediate the delivery

end of the lateral conveyor and the loading boom.

13. In a material delivery installation, a storage bin, material delivering means in the bottom thereof, a lateral conveyor adapted to receive material directly therefrom, an oscillating loading boom mounted adjacent the delivery end thereof, and a rescreening element mounted intermediate the delivery end of the lateral conveyor and the loading boom.

14. In a material delivery installation, adapted to be aligned along and above a railroad track, a storage bin aligned directly above said track, a lateral conveyor aligned along and above said track adapted to receive material directly from the bin, a loading boom mounted adjacent the delivery end of the conveyor and aligned axially therewith, and a rescreening element mounted between the delivery end of the conveyor and the receiving end of the loading boom.

Signed at Chicago, county of Cook and State of Illinois, this 31st day of July, 1922.

FRANK E. MUELLER.
